UNITED STATES PATENT OFFICE

HOBART S. GEER, OF CORONA, NEW YORK, ASSIGNOR TO AMERICAN SAFETY DEVICE CO., OF NEW YORK, N. Y., A CORPORATION OF NEW YORK

HOISTING DEVICE

Application filed November 9, 1931. Serial No. 573,807.

The invention relates to hoisting devices, and more particularly to a hoisting device for building scaffolds of the type wherein scaffold suspending cables are wound upon drums actuated by manually operated means mounted in a suitable supporting frame on one side of the scaffold platform.

It is the primary object and purpose of my present improvements to provide a hoisting device of this character embodying a pair of cable receiving drums together with ratchet means co-operating with each drum, and a single pivotally mounted operating lever actuating the ratchet means in the movement of said lever in one direction to simultaneously rotate the drums and wind the cables thereon.

It is another feature of my invention in one embodiment thereof to pivotally mount the operating lever at one of its ends between the cable drums, said lever carrying independently acting pawls co-operating with ratchets on one end of the respective drums, and additional means on said lever whereby either of the pawls may be retained in an inoperative position, so that the drums can be selectively rotated independently of each other.

It is a further general object of my invention to provide a hoisting device as above characterized, which is of relatively simple mechanical construction, exceedingly strong and durable, and which may be operated with ease and facility, and with complete safety to the workmen standing on the scaffold platform.

The subject matter of the present application, in part, is a continuation of my pending application for patent, Serial No. 524,240, filed March 21, 1931, but in addition to that portion of the disclosure of said application which is incorporated herein, also includes a modified form of the hoisting device, particularly designed for the purpose of lifting comparatively heavy loads.

With the above and other objects in view, the invention consists in the improved hoisting device, and in the form, construction and relative arrangement of its several parts, as will be hereinafter more fully described, illustrated in the accompanying drawings, and

subsequently incorporated in the subjoined claims.

In the drawings wherein I have disclosed several simple and practical embodiments of my invention, and in which similar reference characters designate corresponding parts throughout the several views,—

Figure 1 is a vertical sectional view through one side of a scaffold having the present invention applied thereto, the operating lever for the hoisting device being shown in dotted lines at one end of its normal operating stroke, and in full lines in an extreme position and released from operative connection with the hoisting drums;

Fig. 2 is a front elevation, the supporting frame members and parts of the hoisting drums being shown in section;

Fig. 3 is an enlarged detail sectional view taken on the line 3—3 of Fig. 1;

Fig. 4 is a detail vertical section of a modified embodiment of the invention, designed more particularly for a heavy duty machine;

Fig. 5 is a sectional view taken on the line 5—5 of Fig. 4;

Fig. 6 is a view similar to Fig. 4 showing another alternative form of the device; and

Fig. 7 is a perspective view of certain of the parts shown in Fig. 6.

Referring, for the present, more particularly to Figs. 1, 2 and 3 of the drawings, as therein illustrated, the supporting frame for the hoisting drums may consist of the spaced uprights 5, preferably, though not necessarily, of channel shape in cross section. These uprights are rigidly connected with each other at one or more spaced points by a suitable cross bar 6 and tie rods 7 and 8 respectively. To each of the uprights, may also be secured vertically spaced laterally projecting loop members indicated at 9 to receive guard rails 10 extending between the hoisting devices located adjacent opposite ends of the scaffold platform.

Upon a horizontal shaft 11 rigidly fixed at its ends in the spaced uprights 5, a pair of drums 12 and 13 respectively are mounted for free relative rotation. Each drum at its opposite ends is provided with the usual heads, and the opposed heads of said drums are pro-

vided upon their peripheries with the ratchet teeth 14 and 15 respectively. Upon the tie rod 8 above said drums, spring pressed holding dogs 16 and 17 are pivotally mounted and normally engaged with the ratchet teeth 14 and 15 respectively to hold said drums against rotation in one direction.

Between the drums 12 and 13, one end of the operating lever 18 is pivotally mounted on the fixed shaft 11. Upon opposite sides of this lever, the pawls 19 and 20 are pivotally mounted as at 21 and yieldingly urged by suitable springs 22 into engagement with the respective ratchet teeth 14 and 15 of said drums. At their pivoted ends, each pawl is formed with a downwardly projecting lug 19' and 20' respectively, which in one position of the lever are adapted to abut against the cross bar 6 of the supporting frame, whereby said dogs will be moved out of effective engagement with the ratchet teeth 14 and 15.

For the purpose of illustrating one application of my present invention, I have shown the frame uprights 5 connected at their lower ends to parallel horizontally disposed beams, one of which is indicated at 23. Between the opposite ends of these beams, suitable guide wheels such as that shown at 24 are rotatably mounted and around the same the cable 25 extending downwardly from drum 13 is engaged. The similar cable 26 extends upwardly from the other drum 12. The upper ends of these cables are suitably anchored in the usual manner to a beam or outrigger projecting outwardly from the building frame structure.

The beams 23 support the scaffold platform indicated at 27. Upon the inner side of this scaffold platform, a longitudinally extending stop rail 28 is hingedly mounted as at 29. When this rail is in upright position as seen in Fig. 1, it acts as a stop to limit the downward movement of the drum operating lever 18 and prevents contact of the lugs 19' and 20' of the ratchet pawls with the bar 6.

The cable 26 is engaged with a guiding roller 30 pivotally and slidably supported on the tie rod 7, which insures the proper winding of the cable upon the drum 12.

In installing the scaffolding as above described, before the platform 27 is arranged upon the beams 23, the operators move the levers 18 of the respective hoisting devices downwardly to the position shown in full lines in Fig. 1 of the drawings, urging the same outwardly with the foot until the fingers or lugs 19' and 20' of the ratchet pawls engage the bar 6, thus releasing said pawls from operative engagement with the drum ratchets 14 and 15. The dogs 16 and 17 are also lifted upwardly to the dotted line position shown in Fig. 1 out of engagement with the drum ratchets. The cables

25 and 26 may now be freely unwound from the respective drums and anchored at their upper ends to the overhead beams. Upon release of the dogs 16 and 17, the drums will then be locked against further rotation to permit the cables to unwind therefrom. The levers 18 of the hoisting device are then moved upwardly so that the pawls 19 and 20 are thrown into engagement with the respective ratchets by springs 22. The scaffold platform 27 is now arranged upon the supporting beams 23 and the rail 28 raised to the upright position seen in Fig. 1 of the drawings. It will now be evident that in each downward movement of the operating lever 18, through the medium of the ratchet engaging pawls 19 and 20, the two drums will be simultaneously rotated in an anti-clockwise direction, thereby winding the cables 25 and 26 on the respective drums and raising the scaffold. However, in case of uneven winding of the cables on the drums, either of the pawls 19 and 20 may be manually released from engagement with the ratchet teeth of the respective drums so that one of the drums will remain stationary while the other drum is rotated in the manipulation of the lever 18. If desired, suitable means such as that indicated in Fig. 4 may be provided for holding the pawls in their released positions.

In lowering the scaffold, after disposing of the operating lever in the full line position of Fig. 1, and disengaging the pawls 19 and 20 from the ratchets, the holding dogs 16 and 17 may be manually operated and either simultaneously or independently released from engagement with the respective drum ratchets and thereby permit of the free rotation of the drums in a clockwise direction and the unwinding of the respective cables therefrom.

In Figs. 4 and 5 of the drawings, I have illustrated a heavy duty type of hoisting device in which the drums 12' and 13' are vertically spaced apart in the frame of the hoisting device. The operating lever 18' is pivotally mounted at one of its ends as at 18a between these vertically spaced drums. Upon one side of this lever, a comparatively long pawl 31 projects upwardly and is yieldingly held at its free end in operative engagement with the teeth of the ratchet 14' on the upper drum by means of a suitable spring 32. Upon the opposite side of the lever 18', a comparatively short pawl 33 is pivoted and extends downwardly therefrom and is urged into engagement with the teeth of the ratchet 15' on the lower drum by means of a suitable spring 34. Each of the pawls at its pivoted end is formed with a lug 31' and 33' respectively engaged by an adjustable bolt or screw 35, 36 carried by the lever 18. Upon adjustment of these screws in one direction against said lugs, it will be readily under-

stood that the free ends of the pawls will be thereby thrown out of co-operating engagement with teeth of the respective drum ratchets. In this manner, it will be evident that the two drums may be simultaneously operated on the downward movement of lever 18' to wind the respective cables thereon, or if desired, either of these drums may be thus operated independently of the other. The ratchet pawls are so located with respect to the pivot 18^a and the operating lever 18' is of such length, that in each downward stroke of the lever, the pawls will impart a powerful though relatively short rotative movement to the respective drums.

In Figs. 6 and 7, I have illustrated an alternative of the last described embodiment of the invention, in which separate levers 18^b and 18^c are associated with the respective vertically spaced drums, each of said levers carrying the spring pressed ratchet engaging pawls 37 and 38 respectively for rotating the drums in a winding direction. To the lever 18^b, a connecting bar 39 is pivoted at one of its ends as at 40. The other end of this bar is suitably notched as indicated at 41, to receive a headed stud 42 projecting from one side of the lever 18^b. A pivoted yoke element 43 is mounted in the latter end of bar 39 and is recessed as at 44 to receive one side of the shank of the stud 42. This yoke element carries a threaded rod 45 on which a clamping nut 46 is engaged. It will thus be readily understood that after the stud 42 has been positioned in notch 41 and the yoke element 43 is swung into parallel relation with the bar 39, upon then adjusting the nut 46 into tight clamping engagement against the end of said bar, the two levers are thus connected for simultaneous pivoting movement. Thus, in the manual operation of the upper lever 18^b, both drums will be actuated to wind the respective cables thereon. When it is desired to operate the drums independently of each other, the bar 39 may be readily disconnected from lever 18^b by adjusting the nut 46 and disengaging the yoke member 43 from stud 42. The bar 39 will then hang from its pivot 40 in pendent relation to the lower lever 18^c. The two operating levers can then be independently manipulated.

From the foregoing description considered in connection with the accompanying drawings, the construction, manner of operation and several advantages of my improved hoisting device will be readily and fully understood. It will be evident that both of the described constructions will provide devices of this kind which may be easily operated with minimum manual labor for the lifting of either light or heavy loads. While these described constructions will be efficient and reliable in operation, it will nevertheless be understood that insofar as the essential features of my present disclosure are concerned, the

same may also be embodied in various other alternative structural forms, and I therefore reserve the privilege of resorting to all such legitimate changes in the form, construction and relative arrangement of the several parts thereof as may be fairly embodied within the spirit and scope of the appended claims.

I claim:

1. A hoisting device comprising a rotatably mounted drum, a pivoted operating lever for said drum, a member pivotally mounted on said lever co-operating with the drum to rotate the latter in the movement of said lever in one direction, and a fixed stop engaged by said member upon movement of the lever to an extreme position to hold said member out of operative engagement with the drum.

2. A hoisting device comprising a rotatably mounted drum, a pivoted operating lever for said drum, a member pivotally mounted on said lever co-operating with the drum to rotate the latter in the movement of said lever in one direction, a fixed stop engaged by said member upon movement of the lever to an extreme position to hold said member out of operative engagement with the drum, and an adjustably mounted member adapted to be positioned in the path of movement of the drum operating lever, to limit the movement of the lever towards such extreme position and prevent engagement of the drum actuating member with said stop.

3. A hoisting device comprising a frame, vertically spaced drums rotatably mounted in said frame, a lever pivoted at one end upon the frame between said drums, independently acting devices carried by the lever and co-operating with the respective drums to simultaneously rotate the latter in the movement of said lever in one direction, and separate adjustable means mounted on said lever to selectively move and position said devices out of co-operative relation with the respective drums whereby either of said drums may be rotated independently of the other.

4. A hoisting device comprising a frame, vertically spaced drums rotatably mounted in said frame, a lever pivoted at one end on the frame between said drums, ratchets on the corresponding ends of the drums, a pair of pawls pivotally mounted on the lever and projecting in opposite directions therefrom, spring means yieldingly urging the respective pawls into operative engagement with the respective drum ratchets, and independently adjustable members mounted on the lever and co-operating with the respective pawls to retain the same in an inoperative position relative to the drum ratchets, whereby said drums may be either simultaneously or independently rotated in the movement of said lever in one direction.

5. A hoisting device comprising a frame, spaced drums rotatably mounted in said frame and each having a ratchet at one end,

a single operating lever pivoted at one of its ends between said drums, a pair of pawls pivotally mounted at one of their ends on opposite sides of said lever, a spring acting upon each pawl to yieldingly hold its other end in engagement with one of the drum ratchets, and means adjustably mounted upon the lever for selectively moving said pawls to an inoperative position relative to the associated drum ratchet.

In testimony that I claim the foregoing as my invention, I have signed my name hereto.

HOBART S. GEER.
